Primary Examiner — Lauren D McVey

(57) **CLAIM**

The ornamental design for a label printer, as shown and described.

DESCRIPTION

FIG. 1 is a front elevation view thereof of a label printer, showing our new design.

FIG. 2 is a rear elevation view thereof

FIG. 3 is a right side elevation view thereof

FIG. 4 is a left side elevation view thereof

FIG. 5 is a top view thereof

FIG. 6 is a bottom plan view thereof; and,

FIG. 7 is a top, front and right side perspective view thereof.

The broken lines in the drawings illustrate the portions of the label printer which form no part of the claimed design.
